UNITED STATES PATENT OFFICE.

JOHN H. ALKER, OF PITTSBURG, PENNSYLVANIA, ASSIGNOR TO THE OLIVER IRON AND STEEL COMPANY, OF SAME PLACE.

MANUFACTURE OF GATE-HOOKS.

SPECIFICATION forming part of Letters Patent No. 469,621, dated February 23, 1892.

Application filed December 19, 1891. Serial No. 415,653. (No model.)

To all whom it may concern:

Be it known that I, JOHN H. ALKER, of Pittsburg, in the county of Allegheny and State of Pennsylvania, have invented a new and useful Improvement in the Manufacture of Gate-Hooks, of which the following is a full, clear, and exact description, reference being had to the accompanying drawings, forming part of this specification, in which—

10 Figure 1 is a top plan view of my improved dies in retracted position. Fig. 2 is a front elevation, and Fig. 3 a side view, of the same with one clamping-die removed. Fig. 4 is a view of the blank after the bending operation, and Figs. 5 and 6 are views of the finished article.

Like symbols of reference indicate like parts in each.

My invention relates to the manufacture of 20 "gate-hooks" or the pin portions of gate-hinges; and it consists in improved dies whereby the finished hook is produced from the blank by two strokes of the plunger-die and also in the improved method of forming 25 such hooks, as hereinafter more fully described, and set forth in the claims.

In the drawings, 2 represents the stationary and 3 the movable clamping-die. The die 2 in its front portion is provided with the angled groove 4 and in the rear thereof with the jog or offset 5. In the rear of the offset is the horizontal groove 6, which terminates in a concave recess 7, which is located partly beneath the groove and partly in the shoulder formed by the offset. Immediately beneath the groove 6 is the projecting pin 8, which enters a corresponding aperture 9 in the movable die 3. This pin serves both as a stop for introducing the blank into the 35 groove and sustaining it until the movable die clamps it in position and also as a guide for the movable die to produce an exact registering of the two clamping-dies. The movable clamping-die is provided with the grooves 40 10 and 11, corresponding to the grooves 4 and 6 in the stationary die, and when the dies are closed these grooves form holes in which the blank is placed.

As is clearly shown in Fig. 3, the groove 45 4 consists of two portions, a horizontal portion

4' on the lower inner edge of the die and an angled portion 4" extending upward and outward at an acute angle thereto and upon the inner face of the die. The groove 10 exactly corresponds thereto, and immediately beneath 55 the groove 4 is the stop 12, which is suitably secured to the frame of the machine and is preferably vertically adjustable. In the rear of the clamping-dies is the plunger-die 13, the lower extension 14 of which moves beneath 60 the clamping-dies, and the groove 15 of which registers with the horizontal portions of the grooves 4 and 10 when the clamping-dies are closed. Above the part 14 is the head 16, having upon its front face the groove 17, which 65 terminates in an enlarged recess 18 with outwardly-tapering cone-shaped sides. This recess registers with the hole formed by the grooves 6 and 11 when the clamping-dies are closed and forms the head upon the finished 70 article:

The operation is as follows: A bar being inserted in the groove 4, the movable die 3 is reciprocated by suitable mechanism and clamps the rod in the grooves 4 and 10, it 75 standing therein at a slight angle to the vertical. The plunger-die is then reciprocated, and the extension 14, striking the lower part of the bar, bends the same up into the horizontal portions of the grooves 4 and 10, the 80 groove 15 being suitably curved downwardly at its outer end, so as to prevent cutting of the bar. The movable clamping-die is then retracted and the blank removed, it then being in the form of Fig. 4. The plunger-die having 85 been retracted, this blank is then inserted in the groove 6 and rests upon the pin 8 until clamped by the movable die 3. The plunger-die then moves forward again and the angular portion of the blank is pressed into the 90 head by the recess 18, while at the same time the inner end of the blank is rounded by compression against the concave recess 7, the hook of Figs. 5 and 6 resulting. The object of bending the two portions of the bar at an 95 acute angle to each other is that enough metal may be obtained at the angle to form the head upon the hook. Moreover, in this way the vertical part of the blank is prevented from being pushed upward, as in the old method, 100

and the hook is formed by one stroke, where before several strokes of the plunger-die were necessary to produce the head.

The advantages of the device are obvious.
5 The parts are simple, few in number, and not liable to get out of order, while the entire action is automatic.

Many changes may be made in the form and arrangement of the parts without departing from my invention, since
10

What I claim is—

1. The combination, with clamping-dies having registering grooves, of a plunger-die arranged to move across the end of the hole formed by said grooves, substantially as and for the purposes described.
15

2. The combination, with clamping-dies having corresponding grooves, the two portions of which extend at an angle to each
20 other, of a reciprocating die having a groove arranged to register with one of said portions, substantially as and for the purposes described.

3. The combination, with clamping-dies having mating grooves upon their lower inner edges and corresponding grooves extending upwardly at an acute angle thereto, of a plunger-die having a groove arranged to register with the grooves upon the lower edges
25 of the clamping-dies, substantially as and for the purposes described.

4. The combination, with clamping-dies having registering grooves, of a plunger-die having a recess arranged to register with the
30 ends of the grooves and a groove extending from such recess, substantially as and for the purposes described.

5. The combination, with clamping-dies having registering grooves and a pin and corresponding hole immediately beneath the same, of a plunger-die having a recess arranged to register with the ends of the grooves and a groove extending from such recess, substantially as described.
40

45 6. The combination, with clamping-dies

having registering grooves and a stop beneath the same, of a plunger-die arranged to move across the end of the hole formed by said grooves, substantially as and for the purposes described.
50

7. The combination, with clamping-dies having registering grooves and an adjustable stop beneath the same, of a plunger-die arranged to move across the end of the hole formed by said grooves, substantially as and
55 for the purposes described.

8. The combination, with clamping-dies having two sets of registering grooves, of a plunger-die having an extension arranged to move past the end of one set of grooves and a recess arranged to register with the end of the aperture formed by the other set, substantially as and for the purposes described.
60

9. The combination, with clamping-dies having two sets of registering grooves, of a plunger-die having a grooved extension arranged to move past the end of one set of grooves, and a recess arranged to register with the end of the aperture formed by the other set, substantially as and for the purposes described.
65
70

10. The method of making gate-hooks, consisting in bending a portion of a blank at an acute angle to the remaining portion and then shaping the angled part into a head, substantially as and for the purposes described.
75

11. The method of making gate-hooks, consisting in bending a portion of a blank at an acute angle to the remaining portion, then shaping the angled part into a head, and at the same time rounding one end of the blank, substantially as and for the purposes described.
80

In testimony whereof I have hereunto set my hand this 15th day of December, A. D. 85
1891.

JOHN H. ALKER.
